George Galloway, INVENTOR
BY *Victor J. Evans*
ATTORNEY

Paul M. Hunt, Jr.

WITNESS:

UNITED STATES PATENT OFFICE.

GEORGE GALLOWAY, OF CLEVELAND, OHIO.

ARCH-SUPPORT.

1,401,066.

Specification of Letters Patent. Patented Dec. 20, 1921.

Application filed May 24, 1921. Serial No. 472,227.

To all whom it may concern:

Be it known that I, GEORGE GALLOWAY, a citizen of the United States, residing at Cleveland, in the county of Cuyahoga and State of Ohio, have invented new and useful Improvements in Arch-Supports, of which the following is a specification.

My present invention has reference to an arch support for shoes.

10 My object is to produce a device of this character which shall be of a simple nature, readily arranged in a shoe to effectively support the instep of the user of the shoe, at the same time embodying sufficient resiliency to prevent shocks or jars being inflicted on the user, and having its outer face provided with a removable and compressible facing which serves as a pad for further protecting the foot of the user.

20 The foregoing objects, and others which will appear as the nature of the invention is better understood, may be accomplished by a construction, combination, and operative association of parts, such as is disclosed by the drawings which accompany and which form part of this specification.

In the drawings:—

Figure 1 is a top plan view of the improvement.

30 Fig. 2 is a bottom plan view thereof.

Fig. 3 is a sectional view on the line 3—3 of Fig. 1.

Fig. 4 is a sectional view on the line 4—4 of Fig. 1.

35 As disclosed by the drawings, the body of my improved arch support comprises a member which is divided at its center, and in reality is constructed of two separate members 1—1 respectively. The body is rounded

40 downwardly from its center to adjacent its ends, its said ends being flattened, as at 2. The body, at the central arched portion thereof is rounded transversely in an upward direction from one of its edges to its 45 opposite edge. Thus, one edge is elevated with respect to the other edge of the body, which is also true with respect to the extensions 2, except at the extreme ends thereof. The elevated portion of the body, at the

50 center thereof have the members constituting the same connected by flat spring members 3 and 4 respectively. The spring 3, being arranged at the elevated portion of the body is of a greater strength than the spring

55 4. Both of the springs are shaped to con-

form with the inner concaved shape of the body, and are secured to the members 1 by rivets 5.

By reference to the drawings, it will be seen that the confronting edges of the body sections are not in contacting engagement, the springs 3 and 4, however, holding the said members in proper alinement, and as a consequence, the body members are susceptible to a slight downward movement 65 sufficient to absorb any shocks and jars to which the device may be subjected.

Covering the outer face of the body is a facing of compressible material. This facing projects a slight distance beyond the edges and a suitable distance beyond the ends of the body and is removably held on the body by means 8. The elevated edge of the body is rounded upwardly, as at 9, the facing being also arranged on this portion, 75 and if desired, disposed over the edge of the said upwardly rounded portion 9.

It is believed that the foregoing description, when taken in connection with the drawings will fully set forth the construction and advantages of the improvement to those skilled in the art to which such inventions relate and that further detailed description will not be considered necessary. It is to be understood, however, that I am 85 not to be restricted to the precise shape, material employed, and other details of construction as set forth in this specification and illustrated by the drawings, but am entitled to such changes therefrom as fall 90 within the scope of what is claimed.

Having described the invention, I claim:—

An arch support for shoes comprising a body member constituting two plates which are designed to be arranged in a shoe, said 95 plates having their confronting ends spaced and being rounded downwardly from their said inner to their outer ends, and their outer ends provided with straight extensions, said members being rounded transversely for the major portions of their lengths from one to their opposite edge and the last mentioned edge being further rounded in an upward direction, flat springs on the under face of the body secured to the 100 plates constituting said body, a compressible facing for the said body, and removable means securing the facing on the body.

In testimony whereof I affix my signature.

GEORGE GALLOWAY.
